Des. 194,778
Patented Mar. 12, 1963

194,778

HEEL

Faie J. Joyce, New York, N.Y., assignor to Products of India, Inc., New York, N.Y., a corporation of New York

Filed Sept. 21, 1962, Ser. No. 71,806

Term of patent 7 years

(Cl. D7—5)

FIG. 1

FIG. 2

FIG. 5

FIG. 3

FIG. 6

FIG. 4

FIG. 1 is a perspective view of a heel showing my new design, the broken line showing of a shoe being for purposes of illustration only.

FIG. 2 is a bottom view of the heel;

FIG. 3 is a side view of the heel;

FIG. 4 is a rear view of the heel;

FIG. 5 is a perspective view of the heel viewed from above; and

FIG. 6 is a front view of the heel.

I claim:

The ornamental design for a heel, as shown and described.
